UNITED STATES PATENT OFFICE.

WILLIAM J. BURKE, OF SAN FRANCISCO, CALIFORNIA.

WIND-SHIELD CLEANER.

1,284,232.

Specification of Letters Patent. Patented Nov. 12, 1918.

Application filed December 26, 1917. Serial No. 208,890.

To all whom it may concern:

Be it known that I, WILLIAM J. BURKE, a citizen of the United States, residing at San Francisco, in the county of San Francisco and State of California, have invented a new and useful Wind-Shield Cleaner, of which the following is a specification.

It is the object of this invention to provide a novel means for imparting a continuous reciprocating movement to a pane-wiper, and to improve and to enhance the utility of devices of that type to which the present invention appertains.

One form only of the invention is shown in the drawings, and changes falling within the skill of a mechanic may be made without departing from the spirit of the invention.

In the drawings:

20 Figure 1 shows in elevation, a wind shield to which the present invention has been applied;

Fig. 2 is an end elevation wherein parts are broken away;

25 Fig. 3 is a section on the line 3—3 of Fig. 1.

Although the structure hereinafter described may be used in many different ways, it has been shown in connection with the 30 wind shield of an automobile, comprising a frame 1, carrying a transparent pane 2. A depending bearing 3 is attached by a screw 4 or otherwise to the top portion of the frame 1. A casing 5 is provided, the same 35 having an arm 6 held by a set screw 7 if preferred, to the side portion of the frame 1.

A vertical shaft 8 is journaled in the casing 5 and may be flexible. The shaft 8 may be driven from some part of the speedometer mechanism, but it is essential that some 40 suitable means be provided for rotating the shaft 8 continuously in one direction.

The numeral 9 marks a horizontal drive shaft having oppositely wound threads 45 10 which communicate at their ends as shown at 11. The numeral 12 denotes a rider including a sleeve 14 mounted to slide on the

shaft 9 and having an internal projection 15 adapted to engage the threads 10, one at a time. A head 16 is carried by the sleeve 50 14 and holds a wiper 17 adapted to engage the pane 2. Any suitable means may be employed for operatively connecting the shafts 9 and 8. As delineated, intermeshing bevelled pinions 18 on the shafts are employed 55 for this purpose.

When the shaft 9 is rotated by means of the shaft 8, continuously in one direction, the rider 12 moves in one direction longitudinally of the shaft 9, and then moves 60 back in an opposite direction, the projection 15 on the sleeve 14 coating first with one of the threads 10, and then with the other of the threads.

What is claimed is:

65 The combination of a depending bearing adapted to be suspended from the top rail of a wind shield frame; an arm; means for securing one end of the arm removably to one side portion of a shield frame; a gear 70 casing adapted to be supported from the side rail of a shield frame; a revoluble double threaded shaft having one end journaled in the bearing and adapted to be positioned below the top rail of a shield frame, the 75 other end of the shaft extending into the casing, the shaft having oppositely inclined threads communicating at their ends; a sleeve 80 slidable on the shaft and having means for engaging the threads; a pane-wiper mounted on the sleeve and adapted to contact with a pane, the wiper extending upwardly above and downwardly below the shaft; a second shaft journaled in the casing for rotating the first mentioned shaft; 85 and gearing in the casing for connecting the shafts.

In testimony that I claim the foregoing as my own, I have hereto affixed my signature in the presence of two witnesses.

WILLIAM J. BURKE.
